UNITED STATES PATENT OFFICE.

JACOB A. HYLE, OF PHILADELPHIA, PENNSYLVANIA, ASSIGNOR TO THE RAIL ANCHOR COMPANY, A CORPORATION OF DELAWARE.

COMBINED TIE PLATE AND RAIL ANCHOR.

Application filed June 11, 1923, Serial No. 644,640. Renewed July 3, 1924.

To all whom it may concern:

Be it known that I, JACOB A. HYLE, a citizen of the United States, residing at Philadelphia, in the county of Philadelphia and State of Pennsylvania, have invented 5 certain new and useful Improvements in Combined Tie Plates and Rail Anchors, of which the following is a specification.

This invention pertains to a novel combined tie plate and rail anchor and is especially designed for the purposes of successfully preventing the creeping and spreading of the track rails upon a railway road bed, as well as to retain the said rails in their 15 proper alignment, and to insure a substantially perfect gauge being retained on both sides of the rail under any and all conditions.

The prime object of the invention is to 20 provide a strong, novel, simple, durable, economical, meritorious and thoroughly efficient combined tie plate and rail anchor for the track rails of steam and other railway road beds.

Another object of the invention is to provide a tie plate for the reception of the track rails, the said plate being provided with improved locking means for engaging the base of the rails, said locking means including 25 rotatable members which have a tendency to move into tighter locking engagement with the base portion of the rails during vibration or any longitudinal movement of the rails.

Another object of this invention is to so 30 construct my improved tie plate, that the locking means will be prevented under all conditions from being disengaged with the base of the track rails.

A further object of the invention is the 35 provision of a railway tie plate which is rigidly secured to the usual cross tie, and which embodies a plurality of yielding rotatable locking members adapted to overlap the upper surface of the track rail base, the inner surface of each of said members being suitably roughened and adapted to 40 tightly clamp the upper surface of the track rail at all times.

The foregoing and such other objects as 50 may appear from the ensuing description are attained by the construction, arrangement, location and combination of the several parts hereinafter more fully described, 55 illustrated in the accompanying drawings,

and particularly pointed out in the claims appended hereto, it being understood that slight changes in the precise proportions and minor details of construction may be resorted to without departing from the spirit 60 or sacrificing any of the advantages of the invention.

In the accompanying drawings forming a part of this specification, it will be seen that:

Figure 1 is a plan of the novel plate embodying my invention in its normal position beneath a railroad rail.

Figure 2 is a plan showing the position of the tie plate with respect to the rail before 70 being forced into its normal position.

Figure 3 is an end elevation showing a portion of the track rail with the rotatable locking means overlapping the base of the rail.

Figure 4 is a side elevation of the plate and rail anchoring means detached from the rail.

Figure 5 is an end elevation of a slight modification of the plate and rail anchoring 75 means shown attached to a track rail.

Figure 6 is a plan of the plate and rail anchoring means shown in Fig. 5, detached from the track rail, and

Figure 7 is a side elevation of the device 85 shown in Fig. 6.

In the embodiment of my invention as illustrated the numeral 2 designates the metallic tie plate, preferably formed from rolled steel of the desired quality and dimensions, with a smooth flat upper surface for the reception of the track rail 3. In any suitable or desirable manner two square holes 4 are punched through the plate for the reception of the usual track rail securing spikes, and two round holes are punched therethrough for the reception of the rivets 5, the lower face of the plate being countersunk around each of said round holes for the purpose hereinafter described. Each 90 rivet 5 is preferably formed from cold metal of the desired quality and possessing the required strength, and is adapted to secure to the upper surface of the plate a rotatable rail locking member 6, the lower end of each rivet, after being forced through the member 6 and the round opening formed through the plate, is so spread in any suitable manner, as to tightly, rigidly and completely 100 fill in the countersunk portion, so that said

rivet will not work loose or wobble under the wave motion of the track rail during the movement of the rolling stock thereover.

Each of the rotatable members 6 is substantially circular in contour and provided with a central collar or hub portion 7, against which the outer edge of the rail base is adapted to contact, a depending lug portion 8 formed at its outer end adapted to rest in contact with the upper surface of the plate 2, thereby preventing any tilting tendency of the member, and an inner end portion which is serrated or otherwise suitably roughened on its lower surface 9 adapted to tightly bite, clamp and grip the upper surface of the rail base when the said plate is forced into its normal position beneath the track rail, said member 6 being thinnest at its inner portion and gradually thickened rearwardly, as shown.

By reference to Fig. 2 it will be perceived that the plate is first placed beneath the rail 3 substantially into the position shown, after which by striking the outer edge 10 of said plate with a sledge or heavy hammer the inner lower beveled roughened face of each member 6 will be caused to ride or yieldingly slide inwardly to overlap the slightly inclined upper surface of the rail base until the plate assumes its normal position beneath the base of the rail, as shown in Fig. 1, thereby rigidly and securely clamping the plate of the rail base, after which the usual securing rail spikes are driven through the square holes 4 thereby furnishing additional securing means for both the plate and track rail. In removing the plate from the track rail after the fastening spikes shall have been withdrawn it is simply necessary to strike the edge 11 of the plate with a sledge or heavy hammer when the said plate may be easily detached.

In the slight modification such as shown in Figs. 5, 6 and 7, it will be seen that I employ a flat piece of steel or iron bar 12 of suitable dimensions, which is seated on the upper surface of the plate 13, and having a round hole punched therethrough for the reception of the rivet 5, by which rivet it is suitably secured beneath the rotatable locking member 14, with its inner edge resting in contact with the outer edge of the rail base, and its outer edge terminating with the outer edge of the member 14, said member 14 having a flat surface resting in contact with the bar 12, and its lower roughened inner surface being beveled gradually inward to its terminal point for the purpose hereinbefore described, while the plate 13 is thickest at its outer end and is sloped or beveled inwardly to its inner end, so that when a track rail is seated thereon, the said rail will tilt or lean slightly inwardly which is preferably employed by some of the rail-way systems, as clearly shown in Fig. 5.

The rotatable locking members are preferably formed from drop forge steel of the desired quality and dimensions as to insure the requisite strength to withstand all strains to which they may be subjected, and each member is provided with a slight upwardly extending lug or arrow 15, serving to indicate to the track man engaged in the installation the correct point at which the member should normally rest.

It will be readily obvious that this novel combined tie plate and rail anchor serves as a two way anti-creeper which prevents the track rail from moving either back or forth more than a fraction of an inch, and only sufficient to permit the well known wave motion of the rail which is essential, since the wedge shaped or gradually thickened inner roughened edge portion of each locking member which is in constant contact with the rail will be caused to rotate by the movement of the rail into more rigid and intense contact with the rail and thereby lock the rail from further movement; that the locking members are so constructed and secured to the plate as to retain them in a level position, and to prevent any tendency to bend the rivet by any lifting strain which may be imparted to the overlapping inner edge of said members; that the locking members can be freely rotated before the tie plates are installed, and that each tie plate may be rolled with a serrated or otherwise suitably roughened lower face (not shown) so that it will readily adhere to the cross tie to which it is secured.

It will be understood that this improved device is constructed of such a quality of metal, and all of its parts of such dimensions as to impart the maximum amount of strength for the purposes for which it is intended, and that one of the types of rotatable members herein described may be used on one side of the tie plate and the other type of member on the opposite side or two rotatable locking members of the same construction may be secured to one plate.

Having thus described my invention what I claim and desire to secure by Letters Patent is:

1. A track rail tie plate of the character described comprising a rolled steel plate formed with a smooth flat upper surface, and a pivoted freely rotatable rail locking member secured thereto and disposed at each of two diagonally opposite corners thereof.

2. A track rail tie plate of the character described, comprising a rolled steel plate formed with a smooth flat upper surface, a freely rotatable rail locking member secured thereto and disposed at each of two diagonally opposite corners thereof, and means for pivotally securing said members thereto.

3. A track rail tie plate of the character described, comprising a rolled steel plate

formed with a smooth flat upper surface, a pivoted freely rotatable rail locking member secured thereto and disposed at each of its two diagonally opposite corners, each of said members being formed with a wedge-shaped lower surface overlapping the base of the rail.

4. A track rail tie plate of the character described, comprising a steel plate having secured thereto a freely rotatable circular rail locking member disposed at each side of its upper surface, each member being formed with a wedge-shaped lower face overlapping the upper surface of the rail base, and means for pivotally securing said members thereto.

5. A track rail tie plate of the character described, comprising a steel plate formed with a circular rotatable rail locking member secured to each side of its upper face, each member being formed with a wedge-shaped lower face overlapping the upper surface of the base of the rail, and a rivet passing through said plate and member for locking the member thereto.

6. A track rail tie plate of the character described, comprising a steel plate formed with a smooth flat upper surface, a rotatable rail locking member pivotally secured to the upper face of each side of the plate, each of said members being formed with a

wedge-shaped roughened lower face overlapping the upper surface of the rail base.

7. A track rail tie plate of the character described, comprising a steel plate, a circular freely rotatable rail locking member pivotally secured thereto at each side of the plate and overlapping the upper face of the rail base, each member having a roughened wedge-shaped lower face, and a rivet passing through each member and plate for fastening the members to said plate.

8. A track rail tie plate of the character described, comprising a steel plate, a circular freely rotatable rail locking member disposed at each of two diagonally opposite corners, each member overlapping the upper surface of the rail base and formed with a roughened wedge-shaped lower face, and means for pivotally securing each member to said plate.

9. A track rail tie plate of the character described, comprising a steel plate, a circular freely rotatable rail locking member disposed at each of two diagonally opposite corners, each member overlapping the upper surface of the rail base, a rivet passing through each member and plate for pivotally securing each member to the plate, and each member being formed with a roughened wedge shaped lower face.

JACOB A. HYLE.
